UNITED STATES PATENT OFFICE.

NEWTON K. BOWMAN, OF CANTON, OHIO.

AUTOMATIC MINE-DOOR.

1,374,547.

Specification of Letters Patent. Patented Apr. 12, 1921.

Application filed February 14, 1920. Serial No. 358,673.

To all whom it may concern:

Be it known that I, NEWTON K. BOWMAN, a citizen of the United States, residing at Canton, in the county of Stark and State 5 of Ohio, have invented certain new and useful Improvements in Automatic Mine-Doors, of which the following is a specification.

This invention relates to an improved automatic mine door and has as one of its 10 principal objects to provide a door wherein the operating mechanism therefor will be so constructed and arranged as to facilitate cleaning about the mechanism between the 15 ties of the mine track.

The invention has as a further object to provide a door which will readily respond to its operating mechanism but wherein the door will, under normal circumstances, be 20 effectually held closed.

And the invention has as a still further object to provide a door wherein cushioning means will be provided for absorbing any sudden or undue shocks upon the door operating mechanism so as to prevent the door 25 from being violently thrown open and consequently injured.

Other and incidental objects will appear hereinafter.

30 In the drawings:

Figure 1 is a plan view of a mine door constructed in accordance with the present invention, the operating mechanism at one side of the door only being illustrated,

35 Fig. 2 is a detail of a crank arm carried by one of the leaves of the door,

Fig. 3 is a detail of a crank arm connected to the other leaf of the door,

40 Fig. 4 is a fragmentary vertical section taken on the line 4—4 of Fig. 1, looking in the direction of the arrows,

Fig. 5 is a fragmentary vertical section taken on the line 5—5 of Fig. 1, looking in the direction of the arrows,

45 Fig. 6 is a fragmentary perspective showing a part of the trip mechanism, and

Fig. 7 is a detail perspective showing the mounting for the free end of the trip lever employed.

50 In carrying the invention into effect, I employ a door frame 10 which, as suggested in Fig. 1 of the drawings, preferably stands diagonally of the mine track and mounted to swing within the frame is the mine door.

55 This door is formed of companion leaves 11 and 12 normally overlapping at their inner

vertical margins and arranged to swing in opposite directions. Extending from the leaves are arms 13 and pivotally connected to the end portions of these arms is a rod 60 14 coupling the door leaves to swing in unison. A bumper post 15 is provided and, usually, a fence 16 is arranged to extend between this post and the adjacent vertical post of the door frame, the leaf 11 of the 65 door being designed to engage the fence for limiting the door in its extreme opening movement.

Mounted upon the inner vertical margin of the leaf 11 of the door is a crank arm 70 17 bolted or otherwise secured at its inner end to the leaf and provided, as particularly shown in Fig. 2, with a laterally directed leg 18 resting against the inner vertical strip of the leaf and sustaining the outer 75 end portion of the arm to extend away from the leaf beyond the inner edge thereof. At its outer end the arm is provided with an enlarged substantially triangular shaped head 19 and is slotted, as shown at 20, so 80 that the outer end of the arm is thus, in effect, formed into a clevis. Through the head is provided a plurality of spaced openings 21 and freely received within the slot 20 is one end of a turnbuckle 22 detachably 85 and pivotally connected to the head by a suitable pin engaged through one of said openings. To the opposite end of the turnbuckle is connected a closing spring 23 for the door, this spring being secured to the 90 post 15 in any approved manner. Thus, it will be seen that the spring will constantly urge the door to closed position and, of course, the tension of the spring may be varied by adjusting the turnbuckle. However, due to different conditions arising under practical installation, it is very often found desirable to increase or decrease the leverage of the spring upon the door and thus vary the effective pressure of the 95 spring. As will be seen, this latter result may be accomplished by selectively engaging the pin of the turnbuckle within the series of openings 21 in the head 19, these openings being arranged so that the effective length of the arm 17 may not only be readily increased or decreased but also so that the normal tension upon the spring may be readily varied through proper adjustment of the pin. Bolted or otherwise 100 secured to the inner vertical margin of the leaf 12 of the door is a crank arm 24, the 105

outer end portion of which is preferably curved in the direction of the door frame. Extending at opposite sides of the door is the operating mechanism therefor but 5 since the structure at each side of the door is identical, that at one side only will be described in detail. Secured to suitable ties of the mine track, at proper points along the track, are, as particularly shown in Fig. 10, 6, pairs of spaced brackets 25. As will be noted, these brackets are formed to seat against the vertical side face of a tie and formed on the bracket bases are flanges 26 engaging over the upper face of the tie. As 15 suggested, lag bolts may be employed for securing the brackets in position and pivoted upon the outer ends of the brackets are pairs of sleeves 27, the innermost sleeve of each of said pairs carrying an arm 28. 20 Fitted through each pair of sleeves is a squared rock shaft 29 held by suitable set bolts upon the sleeves and fitted upon the outer end of each of said shafts is an up-standing arm 30 disposed at substantially 25 right angles to the arms 28. It is now to be observed that in mounting each pair of the brackets 25 upon a single tie, access may be readily had between said tie and the next adjacent tie for cleaning out between such ties beneath the rock shafts 29 so that the arms 28 and 30 of said shafts may always freely swing. To the arms 28 are connected links 31 and supported by these links is a 30 preferably channel shaped operating bar 32. 35 The bar is mounted to extend at the inner side of one of the rails of the mine track and, as will be best observed upon reference to Fig. 6, the flange of the bar adjacent the rail is somewhat shorter than the other 40 flange of the bar. The bar is formed of sections, the outermost of which, indicated at 33, provides a trip lever for depressing the bar and opening the door, said section being normally inclined longitudinally. 45 Mounted between adjacent ties of the mine track near the outer end of the section 33 is, as shown in detail in Fig. 7, a saddle plate 34. This plate is provided at its inner 50 end with lateral lugs 35 overhanging the adjacent track ties and receiving lag bolts or other approved fastenings therethrough. The plate extends beneath the adjacent rail of the track and at its outer end portion is 55 provided with spaced longitudinally extending lugs 36, and seated upon these lugs are clamps 37 engaging over the base flange of said rail for thus rigidly sustaining the plate. Rising from the inner end portion 60 of the plate is a stop lug 38 and depending from the plate adjacent the base of this lug is a socket or sleeve 39. Secured upon the section 33 is a pivot post 40 and, as will now be observed upon reference to Fig. 5, 65 this post extends freely through the socket

39 of the saddle plate for thus sustaining the free end portion of the bar section adjacent to the track rail. Extending from the post beneath the bar section is a laterally directed plate 41 upon the lower edge of 70 which is formed a knife edge or V-shaped rib 42 which, under normal conditions, will seat against the saddle plate for supporting the free end portion of the bar section to 75 rock thereon. However, it often proves necessary to elevate the free end portion of the bar section and I accordingly provide spacers 43. These spacers are formed with 80 openings to freely receive the post 40 therethrough and may, as suggested in Fig. 5, be positioned upon the saddle plate abutting the stop lug 38 thereof when the rib 42 will contact the uppermost of said spacers for 85 pivotally supporting the bar section elevated in proper juxtaposition with respect to the adjacent track rail, the post, of course, serving to retain the spacers upon the saddle plate.

Pivotally connected to the upper end of 90 that one of the arms 30 nearest the door is a clevis 44 in which slides a cross head 45 and connected at one end to this cross head is a rod 46 which extends freely through the bight of the clevis and at its opposite 95 end is pivotally connected to the free end of the crank arm 24. The corresponding rod extending at the opposite side of the door is, as shown in Fig. 1, pivotally connected to the crank arm 17. Surrounding 100 the rod to bear between the cross head and the bight of the clevis is a cushioning spring 47. Pivotally upon the upper ends of the other of the arms 30 are pairs of links 48 and extending between said pairs of links as 105 well as between the inner pair and the outer end of the clevis are rods 49. Thus, as will be seen, the operating bar is coupled with the door so that when said bar is depressed by the engagement of a car with the section 110 33 of the bar, the door will be opened. As the car progresses toward the door, the bar will, of course, be held depressed for maintaining the door open and before the rear wheels of the car have left said bar the 115 forward wheels of the car will have moved into engagement with the bar at the opposite side of the door so that the door will be held open until the car has completely passed through the door and progressed some distance at the opposite side thereof 120 when the door will be automatically closed. Should a car approaching the door forcibly come into contact with the section 33 of the bar, the incident shock upon the bar will, 125 as will be seen, be absorbed in maximum degree by the spring 47, so that this spring will prevent such shock from being communicated directly to the door and the door being violently opened.

In conjunction with the closing spring 23 for the door I employ a weighted lever 50. This lever is mounted upon the outer end portion of one of the rock shafts 29 and adjustable longitudinally upon the lever is its weight 51. When the door is closed the lever stands in a horizontal position while when the door is open, the lever will stand in a substantially perpendicular position. Accordingly, as the tension of the spring 23 upon the door is increased, the effect of the weight tending to close the door will be proportionately decreased and vice versa, the weight and spring thus operating conjunctively to maintain a substantially uniform tension upon the door tending to urge the door to closed position.

Having thus described the invention, what is claimed as new is:

1. A device of the character described including a door formed of companion leaves coupled to swing simultaneously in opposite directions, operating means for opening the door including a crank arm secured to one of said leaves, means upstanding near the door and engageable by one of the leaves for limiting said leaves in their opening movement, and a spring extending between the crank arm and said last mentioned means normally holding the door closed.

2. A device of the character described including a door formed of companion leaves coupled to swing simultaneously in opposite directions, operating means for opening the door including a crank arm connected to one of said leaves, a spring connected to said crank arm normally holding the door closed, means whereby the leverage of the spring upon the door may be varied, and means for tensioning said spring.

3. A device of the character described including a door formed of companion leaves coupled to swing simultaneously in opposite directions, operating means for opening the door including a crank arm provided with a head, a spring for normally holding the door closed, and means for adjustably connecting the spring with the head to vary the tension of the spring.

4. In a device of the character described, a door, operating means for opening the door including a crank arm having an enlarged head provided with a plurality of spaced openings therethrough, a closing spring for the door, and means selectively engageable in said openings for connecting the spring with the arm.

5. In a device of the character described, a door, and operating means for opening the door including a trip lever operatively connected with the door, a saddle plate, and a post carried by the lever and freely engaged through the plate.

6. In a device of the character described, a door, and operating means for opening the door including a depressible operating bar operatively connected with the door and formed of sections, one of the sections providing a normally inclined trip lever, a saddle plate, and a post carried by the lever freely engaged through the plate and provided with a rib normally coacting with the plate for pivotally supporting one end portion of the lever.

7. In a device of the character described, a door, and operating means for opening the door including a depressible operating bar operatively connected with the door and formed of sections, one of said sections providing a normally inclined trip lever, a saddle plate, a post upon the lever freely engaged through the plate, and a spacer mounted upon the plate beneath the lever and freely receiving the post therethrough for elevating the free end portion of the lever.

8. In a device of the character described, the combination of a door formed of companion leaves coupled to swing simultaneously in opposite directions, operating means for opening the door including a crank arm connected to one of said leaves, a spring fixed at one end and connected at its opposite end to said crank arm for normally holding the door closed, and means upon the arm whereby the leverage of the spring upon the door may be varied.

9. In a device of the character described, a door, and operating means for opening the door including a trip lever operatively connected with the door, a saddle plate, means upon the lever freely engaged through said plate, and a spacer mounted upon the plate beneath the lever and freely receiving the said means therethrough for elevating the free end portion of the lever.

10. In a device of the character described, a door, and operating means for opening the door including a trip lever operatively connected with the door, a saddle plate, a spacer resting upon said plate and bearing beneath the free end portion of the lever, and means carried by the lever connecting the spacer with the plate.

11. In a device of the character described, a door, and operating means for opening the door including a trip lever operatively connected with the door, a saddle plate having an upstanding stop lug, a post carried by the lever and freely engaging through the plate, and a spacer mounted upon the plate beneath the lever to abut said stop lug and freely receiving the post therethrough for elevating the free end portion of the lever.

In testimony whereof I affix my signature. 125
NEWTON K. BOWMAN. [L.S.]
